UNITED STATES PATENT OFFICE.

JOHN H. BARTLETT, OF OSHKOSH, WISCONSIN, ASSIGNOR TO THE OSHKOSH TRUNK COMPANY, OF OSHKOSH, WISCONSIN, A CORPORATION OF WISCONSIN.

DESIGN FOR A TRUNK.

Application filed March 28, 1925. Serial No. 12,933. Term of patent 14 years.

To all whom it may concern:

Be it known that I, JOHN H. BARTLETT, a citizen of the United States, residing at Oshkosh, in the county of Winnebago and State of Wisconsin, have invented a new, original, and ornamental Design for Trunk, of which the following is a specification, reference being had to the accompanying drawing, forming part hereof.

Figure 2 is an enlarged view of a portion of the trunk to show the surface in more detail than permitted by the scale on which Figure 1 is drawn.

I claim:

The ornamental design for a trunk, as shown.

JOHN H. BARTLETT.
